(57) **CLAIM**

The ornamental design for a jacket as shown and described.

DESCRIPTION

1. Jacket

1.1 : Front

1.2 : Back

1.3 : Left

1.4 : Right

1.5 : Perspective

1.6 : Perspective

Figure 1.1 is a front view of a jacket; figure 1.2 is a rear view thereof; figure 1.3 is a left side view thereof; figure 1.4 is a right side view thereof; figure 1.5 is a perspective view thereof from a first angle; figure 1.6 is a perspective view thereof from a second angle; the broken lines, which circumscribe the zipper, the collar opening, the chest portion and the sleeves, in figures 1.1-1.6 on the surface of the jacket, illustrate the portions of the design, which form no part of the claimed design.

1 Claim, 6 Drawing Sheets(56)
